UNITED STATES PATENT OFFICE.

MELANCTHON E. ZELLER, OF BLUFFTON, OHIO.

DESIGN FOR A LOOP FOR HARNESS.

SPECIFICATION forming part of Design No. 22,383, dated May 2, 1893.

Application filed March 30, 1893. Serial No. 468,388. Term of patent 14 years.

To all whom it may concern:

Be it known that I, MELANCTHON E. ZELLER, of Bluffton, in the county of Allen and State of Ohio, have invented a new and original Design for Trace-Loops for Harness, of which the following is a full, clear, and exact description, reference being had to the accompanying drawings, forming part of this specification, in which—

Figure 1 shows in plan view a trace loop embodying my design. Fig. 2 is a side elevation thereof; and Fig. 3 is a vertical section on the line III—III of Fig. 1.

My design consists in a trace loop having the form substantially as shown in the accompanying drawings and hereinafter described. 2 represents the body of the loop, which is

in form of an open quadrilateral loop having flat surfaces 3, 3, opposite to each other, and at the rear end an upwardly extending 20 oblong loop 4 projecting from one of the surfaces 3. It has also portions 5 projecting transversely from one of the surfaces 3 in a direction opposite to that of the projection of the loop 4. 25

I claim—

The design for trace loops for harness substantially as herein shown and described.

In testimony whereof I have hereunto set my hand.

MELANCTHON E. ZELLER.
